INVENTOR

INVENTOR

UNITED STATES PATENT OFFICE.

AUTHOR W. RAY, OF CLEVELAND, OHIO, ASSIGNOR TO UNITED ENGINEERING & FOUNDRY COMPANY, OF PITTSBURGH, PENNSYLVANIA, A CORPORATION OF PENNSYLVANIA.

REEL.

Application filed September 21, 1923. Serial No. 664,131.

The present invention relates broadly to reels, and more particularly to reels of a character adaptable for use in steel or wire mills for coiling rod, strip or wire, herein-
5 after referred to as "stock," although the utility of the invention is not limited in this respect.

At the present time it is quite customary to reel lengths of material either while being 10 positively delivered to the reeling mechanism, such material being hereinafter designated as "moving material," or to coil the same from supports, carriers or reels, such material being referred to as "stationary material." When coiling either moving or stationary material, it is desirable to take up the slack as quickly as possible and thereafter coil at a lower speed. If a manually 15 operable decelerating control is provided it has been found that frequently such control is operated so late that the material is placed under a sudden tension and the inertia of the 20 reel parts is such that the material is snapped.

In accordance with the present invention there is provided a reel the speed of operation of which is automatically controlled by the material being coiled, such material preferably being effective for varying the speed 25 of the prime mover which drives the reel.

In the accompanying drawings I have shown for purposes of illustration a preferred embodiment of the present invention, it being understood that the drawings do 30 not define the limits of my invention as changes may obviously be made in the construction and operation disclosed without departing from the spirit of my invention or scope of my broader claims.

40 In the drawings—

Figure 1 is a top plan view of one form of reel embodying the present invention.

Figure 2 is a transverse sectional view on the line 2—2 of Figure 1 looking in the direction of the arrows.

Figure 3 is an end elevation of the construction illustrated in Figure 2; and

Figure 4 is a detail sectional view on the line 4—4 of Figure 1.

50 In carrying out the present invention, in accordance with the preferred embodiment

thereof, there may be provided a suitable base 2 adapted to support a prime mover 3 such as an electric motor, by means of which the various parts of the reel may be operated. The prime mover may be operatively connected through suitable gearing 4 with a shaft 5 journaled in bearings on the base 2 and extending longitudinally thereof substantially parallel to the motor shaft. The 60 shaft 5 in turn carries a pinion 6 meshing with a gear 7 on an upper shaft 8 journaled in a frame 9 mounted to pivot about the shaft 5.

The movable frame 9 has a projecting 65 shelf 10 through which pass guide rods 11 having pivotal mountings 12 at their lower ends with the base 2. Each of these rods is provided with a lower compression spring 13 bearing at its lower end against a collar 70 14 and at its upper end against a head 15 having a hemispherical upper bearing surface in the shelf 10. These springs are of such scale as to normally sustain the weight of the movable frame and hold it in prede- 75 termined position. Carried by the upper ends of the rods 11 are compression springs 16 having a similar bearing engagement with the upper side of the shelf 10 and adapted to have the compression thereon varied by 80 suitable adjusting means 17. These springs tend to restrict the pivotal movement of the frame 9 about the shaft 5 in a counter-clockwise direction as viewed in Figures 2 and 3.

In order to cushion and partially check the return movement of the frame 9, there may be provided one or more dash pots 18 having pistons 19 pivotally connected by piston rods 20 to the shelf 10. Each of the dash 85 pots may have an air connection 21 provided with a controllable air opening 22 adapted to be regulated by the valve 23, and with a check valve 24 tending to restrict downward movement of the piston in the cylinder but permitting relatively unrestricted upward movement thereof within the capacity of the opening 22.

If desired, the movement of the frame 9 in both directions may be positively controlled by an oil cylinder 25 having a bypass connection 26 controlled by a needle

valve 27. By regulating the position of the needle valve it will be obvious that rapidity of movement of the frame may be accurately controlled.

5 The upper shaft 8 carries at one end thereof a reel 28 on which is adapted to be coiled the stock being handled. This reel rotates in a clockwise direction as viewed in Figure 2, and the stock S, as represented by 10 chain lines moves in the direction of the arrow A. During the initial operation of the reel for the purpose of taking up slack, the frame 9 will occupy substantially the position shown in Figure 2. As the tension on the stock increases, however, the entire frame 9 will be swung in a counter-clockwise direction. Advantage is taken of this movement for controlling the speed of 15 rotation of the reel to automatically reduce its speed in accordance with the tension. This may be accomplished by connecting a portion of the frame 9 to a link 29 which is in turn operatively connected to the arm 30 of a suitable rheostat or controller 25 31 for the prime mover. The construction of the controller 31 will be such that as the arm 30 is swung in a counter-clockwise direction, the speed of the motor will be decreased, while as it is swung in the opposite 30 direction the speed of the motor is automatically increased. In this manner the motor speed is decelerated as soon as the slack in the stock is taken up and the possibility of snapping the stock is thereby obviated.

40 The advantages of the present invention arise from the provision of a reel adapted to automatically be operated at a plurality of different speeds determined by the tension of the material being reeled, such tension preferably being effective for changing the speed of the driving motor.

I claim:

1. In a material handling apparatus, a 45 rotatable member adapted to effect longitudinal movement of the material being handled, means for driving said member, supporting means for said member permitting lateral movement thereof under the tension of the material, and means effective upon lateral movement of said member for changing the speed of the driving means.

55 2. In a material handling apparatus, a rotatable member adapted to effect longitudinal movement of the material being handled, means for positively driving said member, supporting means for said member permitting lateral movement thereof under the tension of the material, and means effective upon lateral movement of said member for changing the speed of the driving means.

60 3. In a material handling apparatus, a reel, means for rotating the same, means 65 supporting the reel for bodily movement un-

der the tension of the material being coiled, and means operative upon such movement for changing the speed of the driving means.

4. In a material handling apparatus, a 70 reel, means for positively rotating said reel, means supporting said reel for bodily movement under the tension of the material being coiled, and means operative upon such movement for changing the speed of the 75 driving means.

5. In a coiling apparatus, a reel supported for bodily movement during the reeling, driving mechanism for the reel, means controlled by the movement of the reel for 80 varying the speed of the reel, a variable resisting device for resisting the movement of the reel in one direction arranged to vary the stress on the resisting device as the reel is moved, and a shock absorber for resisting 85 the return movement of the reel.

6. In a coiling apparatus, a reel supported for bodily movement during the reeling, driving mechanism for the reel, means controlled by the movement of the reel for 90 varying the speed of the reel, a variable resisting device for resisting the movement of the reel in one direction arranged to increase the stress on the resisting device as the reel is moved in one direction, and a 95 dash-pot for resisting the return movement of the reel.

7. In a material handling apparatus, a reel, a prime mover for rotating the same, supporting means for the reel, said means 100 permitting bodily movement thereof under the tension of the material being reeled, means operable upon such movement for changing the speed of the prime mover, and means to vary the stress on the supporting 105 means as the reel support is moved.

8. In a material handling apparatus, a base, a reel frame pivotally mounted on said base, a reel carried on the frame, variable resisting means controlling the pivotal 110 movement of the reel frame for varying the stress on the frame as the frame is moved, a prime mover operatively connected to the reel, and means operable upon pivotal movement of the reel frame for varying the 115 speed of the prime mover.

9. In a material coiling apparatus, a reel movable toward and from the material being reeled, variable resisting means controlling the movement of the reel as the pull on the 120 reel varies, a prime mover operatively connected to the reel, and means operable upon such movement of the reel for varying the speed of the prime mover.

10. In a material coiling apparatus, a reel, a reel frame permitting bodily movement of the reel, driving means for the reel, control means effective for varying the speed at which the reel is driven, a connection between the reel frame and the con- 125

trol means for actuating said control means upon movement of the reel frame, and means to vary the stress on the reel frame during the movement thereof.

- 5 11. In a material coiling apparatus, a reel adapted for bodily movement, means for rotating the reel, control means adapted to vary the speed of rotation of the reel, actuating means connected to the control means and movable with bodily movement of the reel for actuating the control means, and a spring abutment for the reel arranged to increase the pressure exerted against the reel as the reel is moved in one direction.

In testimony whereof I have hereunto set my hand.

ARTHUR W. RAY.
